(57) **CLAIM**

The ornamental design for a container for a nasal dilator device, as shown and described.

DESCRIPTION

FIG. 1 is a top, right perspective view of a container for a nasal dilator device, showing our new design, in a closed position;

FIG. 2 is a bottom, left perspective view thereof;

FIG. 3 is a front elevation view thereof;

FIG. 4 is a rear elevation view thereof;

FIG. 5 is a top plan view thereof, showing Axis **21-21**;

FIG. 6 is a bottom plan view thereof;

FIG. 7 is a right side elevation view thereof;

FIG. 8 is a left side elevation view thereof;

FIG. 9 is a top, right perspective view thereof, shown with the lid open halfway;

FIG. 10 is a top, right perspective view thereof, shown in an open position;

FIG. 11 is a bottom, left perspective view of FIG. 10;

FIG. 12 is a front elevation view of FIG. 10;

FIG. 13 is a rear elevation view of FIG. 10;

FIG. 14 is a right side elevation view of FIG. 10;

FIG. 15 is a left side elevation view of FIG. 10;

FIG. 16 is a top plan view of FIG. 10;

FIG. 17 is a bottom plan view of FIG. 10;

FIG. 18 is the same top, right perspective view as FIG. 10, showing axis **19-19**;

FIG. 19 is a cross-sectional view thereof, taken along Axis **19-19** as shown in FIG. 18;

FIG. 20 is a right side view of FIG. 19 cross-section;

FIG. 21 is an alternate cross-sectional view thereof, taken along Axis **21-21**, as shown in FIG. 5; and,

FIG. 22 is an exploded top, right perspective view thereof, shown in an open position.

The dot-dash broken lines of FIGS. 5 and 18 are included to indicate cross-sectional plane lines while all other broken lines are included for the purpose of showing portions of the container for a nasal dilator device; the features shown in broken lines form no part of the claimed design.
